UNITED STATES PATENT OFFICE.

ETTORE MARAZZI, OF MILAN, ITALY.

MACHINE-GUN MOUNTING.

Application filed May 26, 1924. Serial No. 716,054.

To all whom it may concern:

Be it known that I, ETTORE MARAZZI, a subject of the Kingdom of Italy, and residing at Milan, Via Giason del Maine 13, in the Kingdom of Italy, have invented certain new and useful Improvements in Machine-Gun Mountings, of which the following is a specification.

This invention relates to an automatic 10 mounting for machine guns so arranged that it may turn upon its axis and characterized by its capacity to automatically raise or lower the machine gun by pressure exercised by the pilot upon a seat which is a part of 15 the appliance.

This action can be obtained by a system of pulleys one of which is attached to the seat in question and carries a cable passing upon said pulleys and fixed on at one of its ends 20 to a movable framework forming the turnable portion of the mounting for machine guns, whilst the other end is fixed to a tube carrying the machine gun and in such a manner that any movements of the seat are 25 transmitted to the machine gun thus made to displace it vertically.

In order to allow the machine gun support to turn upon its vertical axis the whole of the movable part can be suspended from 30 a fixed ring or fitted on to a specially designed base on which it acts as a pivot. The former of said forms of construction is particularly suited for aeroplanes and air ships, whereas the latter is especially useful 35 in the case of submarine chasers etc.

The invention may be better understood by referring to the annexed drawing, which shows the construction of the two types of support.

40 In said drawing:

Fig. 1 is a perspective view of an automatic support for machine guns arranged on the suspension ring principle;

Fig. 2 is a perspective view of an automatic support for machine guns utilizing the pedestal principle of mounting in said view the weapon being shown in its completely lowered position;

Fig. 3 is a perspective view of an automatic support for machine guns utilizing the pedestal principle of mounting, in said view the weapon being shown in its highest raised position;

Fig. 4 shown how the machine gun holder can be controlled by the pulley system;

Fig. 5 is a detail in sectional view of the

automatic support for machine guns of the kind utilizing the pedestal principle, that is like as illustrated on Figs. 2 and 3.

In all drawings the same numbers represent similar parts.

Referring to Fig. 1, —1— is a ring which is fixed by means of lugs —2— on to the aeroplane or boat in which the machine gun support is fitted; —3— is a ring movable on ring —1— and held in position by guides —4—; —5— is a tube inside which slides tube —6— carrying at its extremity fork —7— into which is fitted the machine gun, said tube —5— being fixed to the movable ring —3—; —8— is a framework made up of four tubes carrying the seat —9— by means of a steel piece —10—; —11— is a piece welded on the top end of tube —5— and which serves to fix this tube to ring —3—; —12— are tubular stays which are designed to strengthen the tube —5—; —14— are tubular stays connecting the framework —13— with the movable rings —3—, said tubular stays —14— being strengthened by means of the stays —16—; —17— is a pulley fixed under the seat —9—; —18— is a pulley mounted upon a lever —33— which is pivotally disposed upon one of the tubular stays —14—, said lever —33— being apt to be fixed in its highest raised position upon this stay —12— by means of a taper pin —34— (Fig. 4); —19— is a metallic cable passing upon the pulleys —17— and —18— and fixed at the extremity of tube —6—; —21— is a cam lever which works on a sleeve —22— attached to tube —5—, this latter being split in such a way that on engaging with cam —21— it locks tube —6— in any desired position.

The whole of the ring —3—, tube —5— tubular stays —12—, framework —13— and tubular stays —14— forms the moving framework of the support. The seat —9— and tube —6— constitute the parts of the support which produce the vertical movement of the machine gun.

In the form of construction illustrated in Figs. 2, and 3, the tube —5— is fitted on to the cylinder —23— by means of piece —11— and stays —14—. Piece —11— also serves for hinging the framework —8— to which in turn, as in the case of the type first described, is fixed the seat —9—.

Inside tube —5— slides the tube —6— carrying the fork —7—. The movement of —6— is controlled again by the cable —19—

passing over pulleys —17— and —18—. It is slipped over hook —20— at one end and fixed at the other on to the lower extremity of tube —6—.

- 5 Cylinder —23— which forms with tube —5— and stays —14— the revolving part of the support is fixed on to a fixed cylinder —25— which with legs —26— forms the base of the support and acts as a pivot.
- 10 Cylinder —23— is provided with a conical ring —27— working on a conical ring —28— of the cylinder —25—, the ring —27— being kept in position upon the ring —28— by means of two clips —39— connected together by bolts passing through lugs —30— (as is indicated on Fig. 5). —31— and —32— are holes for lubricating cylinders —23— and —25—.

20 The operation of the supports described is very simple.

In order to fire above, that is to point the machine gun vertically, the pilot grasps the machine gun and places his weight upon seat —9—, this immediately pulls the cable 25 and makes tube —6— slide upwards thus pivoting the machine gun and displacing the nozzle into a position nearing the vertical.

In order to fire downwards it is only necessary to release the pressure from the seat 30 when the weight of the machine gun will lower tube —6— thus obtaining the necessary change in aim.

Obviously in each case the grip on the gun handle is lowered and raised respectively.

35 Any intermediate position of the machine gun may be easily obtained by the pilot, when he, without completely releasing the pressure from the seat, raises more or less his body from the same, in such a manner as to 40 cause the seat to remain less or more brought down.

The machine gun may be fixed in any intermediate position by the use of cam —21—; although in an aerial fight this is seldom 45 necessary.

When the machine gun is not required, it 50 may be lowered so that it does not offer unnecessary resistance to the air by removing the taper pin —34— and turning the lever —33— with the pulley —18— in the lower position in which they are represented in dotted lines on Fig. 4; in such a manner as to release the tension of the cable —19—.

Obviously the details of construction may 55 be varied considerably without departing from the general principle laid down in this invention.

The appliance described offers many important advantages over the supports hitherto used which generally rely upon springs or similar appliances for raising or lowering the machine gun and actuated by the hands of the pilot. Their mobility is not suffi-

ciently great to make the rapid change of direction necessary with a fast moving body 65 such as an aeroplane.

The supports designed on this principle satisfy completely the modern requirements of aerial warfare, because owing to the rapidity with which it may be moved the 70 aim of the gun can be kept constantly upon the object under fire, and by its use an intensity of fire may be kept up, impossible with other supports.

Another advantage lies in the fact that 75 two or three machine guns may be mounted on the fork of the support provided their total weight does not exceed 88 lbs.

The machine guns may be fired together or may be used as reserve to one another. 80

Having now particularly described and ascertained the nature of my said invention and in what manner the same is to be performed, I declare that what I claim is:

1. An automatic mounting for machine 85 guns including a movable frame, a machine gun carrier slidable vertically in said frame, a vertically movable seat for the gunner, and means connecting the seat with the carrier for effecting vertical movement of the latter 90 in response to movement of the seat.

2. An automatic mounting for machine 95 guns including a movable frame, a machine gun carrier slidable vertically in said frame, a vertically movable seat for the gunner, and means connecting the seat with the carrier for effecting vertical movement of the latter in response to movement of the seat, said 100 means acting to produce movement of the carrier in opposition to the movement of the seat.

3. An automatic mounting for machine 105 guns including a movable frame, a machine gun carrier slidable vertically in said frame, a vertically movable seat for the gunner, and means connecting the seat with the carrier for effecting vertical movement of the latter in response to movement of the seat, said 110 means including pulleys carried respectively by the frame and seat, and a flexible member extending over said pulley and having its ends secured to the gun carrier and frame, respectively.

4. A machine gun mounted as claimed in 115 claim 1 characterized in that the movable frame is suspended from a fixed ring by means of a second ring forming part of the frame and mounted to turn about the first ring.

5. A machine gun mounted as claimed in 120 claim 1 characterized by the provision of a base including a cylindrical member constituting a support for the frame.

In testimony whereof I affix my signature.

ETTORE MARAZZI.
